[57] **CLAIM**

The ornamental design for a cabinet-top lavatory, substantially as shown and described.

DESCRIPTION

FIG. 1 is an isometric view of a lavatory embodying my new design;

FIG. 2 is a top plan view thereof;

FIG. 3 is a right side elevational view thereof, the left side being a mirror image of the right side shown;

FIG. 4 is a front elevational view thereof;

FIG. 5 is a rear elevational view thereof; and

FIG. 6 is a bottom plan view thereof.

The broken line representation of openings in FIGS. 1, 2 and 6 are for purposes of illustration only.

FIG. 1

F - G.2

FIG. 3

FIG. 4

FIG. 5

F - G.6
